WITNESS:

UNITED STATES PATENT OFFICE.

DAVID F. PRISER, OF NORTH MANCHESTER, INDIANA, ASSIGNOR, BY DIRECT AND MESNE ASSIGNMENTS, TO INSTANT WATER HEATER COMPANY, OF NORTH MANCHESTER, INDIANA, A CORPORATION OF INDIANA.

WATER-HEATING DEVICE.

Application filed March 24, 1923. Serial No. 627,429.

To all whom it may concern:

Be it known that I, DAVID F. PRISER, a citizen of the United States, residing at North Manchester, in the county of Wabash 5 and State of Indiana, have invented new and useful Improvements in Water-Heating Devices, of which the following is a specification.

This invention relates to water heaters 10 and has for an object the provision of means for utilizing water or steam of a heating plant for the purpose of heating water in a water supply system.

Another object of the invention is the 15 provision of means for the above purpose which is simple in construction and which may be connected both in a heating system and a water supply system, whereby water in the latter may be subjected to the heat 20 of the former, first for initial heating and again for final heating, in the passage of said water through the water system.

With the above and other objects in view, the invention further includes the following 25 novel features and details of construction, to be hereinafter more fully described, illustrated in the accompanying drawings and pointed out in the appended claims.

In the drawings:—
30 Figure 1 is an elevation of the invention.
Figure 2 is a longitudinal sectional view of the same.

Figure 3 is a transverse section.
Referring in detail to the drawings, 35 wherein like characters of reference denote corresponding parts, the reference character 10 indicates a casing which may be of any desired length and which includes an inner passage 11 and an outer passage 12, the said 40 passages extending longitudinally of the casing and being closed at their ends.

To provide a casing of this structure there is utilized an inner cylindrical member or 45 pipe 13 and an outer cylindrical member or pipe 14, the former extending through and supporting the latter. Extending from the pipe 13 and communicating with the inner passage 11 is a pipe 15, which is adapted to be connected in the distributing system of 50 a steam or hot water plant, so that steam or water from the latter may enter and travel through the passage 11. At the opposite end of the casing and connected to the inner pipe 13 so as to communicate with the

inner passage 11 is a pipe 16 which may 55 form a suitable source of distribution to the radiator or radiators of the heating plant.

Extending longitudinally through the inner passage 11 is a pipe 17 which may be connected with a suitable source of water 60 supply, such as the water supply system of a building, the opposite end of this pipe extending through the opposite end of the casing and being connected to the outer pipe 14 so as to provide communication with the outer passage 12, as shown at 18. Suitable reducing nipples or similar elements 20 may be provided for mounting and supporting the casing 10 upon the pipe 17.

Extending from the casing opposite the 70 point of connection 18 is a discharge pipe or outlet 21 from which extends a pipe 22 and this last mentioned pipe is adapted to provide means of water distribution, a dirt trap 23 being preferably connected at the 75 juncture of the pipes 21 and 22.

It will be apparent from the foregoing description and accompanying drawings that steam or hot water passing into the casing through the pipe 15 will travel 80 through the inner passage 11, while water from a water system or other source of supply passing through that portion of the pipe 17 within the casing will be subjected to heat from the water or steam within the 85 passage 11, where it will be initially heated. This water will then enter the casing through the connection 18 and pass through the outer passage 12 and will be again subjected to heat from the water or steam passing 90 through the passage 11, so that heating of water passing through the water supply system will be thoroughly and practically instantaneously heated. The heated water may then be conducted to a suitable point 95 or points through the distributing pipe 22.

The invention will thus provide means which may be connected within a heating system and water supply system, whereby water drawn from the latter will be instantaneously and thoroughly heated in any 100 quantity desired.

The invention is susceptible of various changes in its form, proportions and minor details of construction and the right is herein reserved to make such changes as properly fall within the scope of the appended 105 claim.

Having described the invention what is claimed is:—

5 A water heater comprising spaced inner and outer cylinders, spacing nipples connecting the inner and outer cylinders and providing an outer water passage closed at each end and an inner steam passage, said steam passage having steam inlet and outlet ports, means closing the opposite ends

of the steam passage, a water supply pipe 10 extending longitudinally through the steam passage and having one of its ends in communication with the water passage at one end thereof and having a water outlet adjacent its opposite end. 15

In testimony whereof I affix my signature.

DAVID F. PRISER.
